[57] ABSTRACT

An address counter which advances 12 consecutive counts, jumps back 12 counts, advances forward 4 consecutive counts, jumps forward 8 counts, and then repeats the same process in a cyclic fashion.

EVEN/ODD REPEAT ADDRESS COUNTER

This invention relates to a centralized automatic message accounting system and, more particularly, it relates to an even/odd/repeat address counter used in the system.

In the hereinafter described centralized automatic message accounting system, the call processor has to read a pair of memory words, each 26 bits per word, every system cycle, and after performing the necessary logic functions, return those two words, either modified or unmodified to the core memory for storage. Also, the first two pairs of words in each group of six pairs has to be accessed again after the sixth pair. This function allows the call processor to update the various internal record keeping functions performed by the call processor. The arrangement and operation is such that the call processor accesses the core memory to read restore and clear/write 12 consecutive words, and then read/write and clear/write the first four words again. Such a process calls for the address generator dedicated to the call processor to advance forward 12 consecutive counts, jump back 12 counts, advance forward four consecutive counts, jump forward eight counts, and then repeat the same process in a cyclic fashion.

Accordingly, it is an object of the present invention to provide an even/odd, repeat address counter which is applicable for use with such a call processor.

Other objects of the invention will in part be obvious and will in part appear hereinafter.

The invention accordingly comprises the several steps and the relation of one or more of such steps with respect to each of the others and the apparatus embodying features of construction, combination of elements and arrangement of parts which are adapted to effect such steps, all as exemplified in the following detailed disclosure, and the scope of the invention will be indicated in the claims.

For a fuller understanding of the nature and objects of the invention, reference should be had to the following detailed description taken in connection with the accompanying drawings, in which:

FIG. 1 is a schematic block diagram of the centralized automatic message accounting system;

FIG. 2 is an illustration of one of the call processor's call stores;

FIG. 3 is a portion of the memory logic subsystem access assignment chart;

FIG. 4 is a block diagram schematic of the address generator; and

FIG. 5 is an illustration of the address advance mode.

Similar reference characters refer to similar parts throughout the several views of the drawings.

DESCRIPTION OF THE INVENTION

Referring now to the drawings, in FIG. 1 the centralized automatic message accounting system is illustrated in block diagram, and the functions of the principal equipment elements can be generally described as follows. The trunks 10, which may be either multi-frequency (MF) trunks or dial pulse (DP) trunks, provide an interface between the originating office, the toll switching system, the marker 11, the switching network 12, and the billing unit 14. The switching network 12 consists of three stages of matrix switching equipment between its inlets and outlets. A suitable distribution of

links between matrices are provided to insure that every inlet has full access to every outlet for any given size of the switching network. The three stages, which consist of A, B and C crosspoint matrices, are interconnected by AB and BC links. The network provides a minimum of 80 inlets, up to a maximum of 2,000 inlets and 80 outlets. Each inlet extends into an A matrix and is defined by an inlet address. Each outlet extends from a C matrix to a terminal and is defined by an outlet address.

Each full size network is divided into a maximum of 25 trunk grids on the inlet side of the network and a service grid with a maximum of 16 arrays on the outlet side of the network. The trunk grids and service grid within the networks are interconnected by the BC link sets of 16 links per set. Each MF trunk grid is provided for 80 inlets. Each DP trunk grid is provided for 40 inlets. The service grid is provided for a maximum of 80 outlets. A BC link is defined as the interconnection of an outlet of a B matrix in a trunk grid and an inlet of a C matrix in the service grid.

The marker 11 is the electronic control for establishing paths through the electromechanical network. The marker constantly scans the trunks for a call for service. When the marker 11 identifies a trunk with a call for service, it determines the trunk type, and establishes a physical connection between the trunk and a proper receiver 16 in the service circuits 15.

The trunk identity and type, along with the receiver identity, are temporarily stored in a marker buffer 17 in the call processor 18 which interfaces the marker 11 and the call processor 18.

When the call processor 18 has stored all of the information transmitted from a receiver, it signals the marker 11 that a particular trunk requires a sender 19. The marker identifies an available sender, establishes a physical connection from the trunk to the sender, and informs the call processor 18 of the trunk and sender identities.

The functions of the receivers 16 are to receive MF 2/6 tones or DP signals representing the called number, and to convert them to an electronic 2/5 output and present them to the call processor 18. A calling number is received by MF 2/6 tones only. The receivers will also accept commands from the call processor 18, and interface with the ONI trunks 20.

The function of the MF senders are to accept commands from the call processor 18, convert them to MF 2/6 tones and send them to the toll switch.

The call processor 18 provides call processing control and, in addition, provides temporary storage of the called and calling telephone numbers, the identity of the trunk which is being used to handle the call, and other necessary information. This information forms part of the initial entry for billing purposes in a multi-entry system. Once this information is passed to the billing unit 14, where a complete initial entry is formatted, the call will be forwarded to the toll switch for routing.

The call processor 18 consists of the marker buffer 17 and a call processor controller 21. There are 77 call stores in the call processor 18, each call store handling one call at a time. The call processor 18 operates on the 77 call stores on a time-shared basis. Each call store has a unique time slot, and the access time for all 77 call stores is equal to 39.4 MS, plus or minus 1 percent.

The marker buffer 17 is the electronic interface between the marker 11 and the call processor controller 21. Its primary functions are to receive from the marker 11 the identities of the trunk, receiver or sender, and the trunk type. This information is forwarded to the appropriate call store.

The operation of the call process controller revolves around the call store. The call store is a section of memory allocated for the processing of a call, and the call process controller 21 operates on the 77 call stores sequentially. Each call store has eight rows and each row consists of 50 bits of information. The first and second rows are repeated in rows 7 and 8, respectively. Each row consists of two physical memory words of 26 bits per word. Twenty-five bits of each word are used for storage of data, and the twenty-sixth bit is a parity bit.

The call processor controller 21 makes use of the information stored in the call store to control the progress of the call. It performs digit accumulation and the sequencing of digits to be sent. It performs fourth digit 0/1 blocking on a 6 or 10 digit call. It interfaces with the receivers 16, the senders 19, the code processor 22, the billing unit 14, and the marker buffer 17 to control the call.

The main purpose of the code processor 22 is to analyze call destination codes in order to perform screening, prefixing and code conversion operations of a nature which are originating point dependent. This code processing is peculiar to the needs of direct distance dialing (DDD) originating traffic and is not concerned with trunk selection and alternate routing, which are regular translation functions of the associated toll switching machine. The code processor 22 is accessed only by the call processor 18 on a demand basis.

The billing unit 14 receives and organizes the call billing data, and transcribes it onto magnetic tape. A multi-entry tape format is used, and data is entered into tape via a tape transport operating in a continuous recording mode. After the calling and called director numbers, trunk identity, and class of service information is checked and placed in storage, the billing unit 14 is accessed by the call process controller 21. At this time, the call record information is transmitted into the billing unit 14 where it is formated and subsequently recorded on magnetic tape. The initial entry will include the time. Additional entries to the billing unit 14 contain answer and disconnect information.

The trunk scanner 25 is the means of conveying the various states of the trunks to the billing unit 14. The trunk scanner 25 is connected to the trunks by a highway extending from the billing unit 14 to each trunk. Potentials on the highway leads will indicate states in the trunks.

Each distinct entry (initial, answer, disconnect) will contain a unique entry identity code as an aid to the electronic data processing (EDP) equipment in consolidating the multi-entry call records into toll billing statements. The billing unit 14 will provide the correct entry identifier code. The magnetic tape unit 26 is comprised of the magnetic tape transport and the drive, storage and control electronics required to read and write data from and to the 9 channel billing tape. The read function will allow the tape unit to be used to update the memory.

The recorder operates in the continuous mode at a speed of 5 inches per second, and a packing density of

800 bits per inch. Billing data is recorded in a multi-entry format using a nine bit EBCDIC character (extended binary coded decimal interchange code). The memory subsystem 30 serves as the temporary storage of the call record, as the permanent storage of the code tables for the code processor 22, and as the alterable storage of the trunk status used by the trunk scanner 25.

The core memory 31 is composed of ferrite cores as the storage elements, and electronic circuits are used to energize and determine the status of the cores. The core memory 31 is of the random access, destructive readout type, 26 bits per word with 16 K words.

For storage, data is presented to the core memory data registers by the data selector 32. The address generator 33 provides the address or core storage locations which activate the proper read/write circuits representing one word. The proper clear/write command allows the data selected by the data selector 32 to be transferred to the core storage registers for storage into the addressed core location.

For readout, the address generator 33 provides the address or core storage location of the word which is to be read out of memory. The proper read/restore command allows the data contained in the word being read out, to be presented to the read buffer 34. With a read/restore command, the data being read out is also returned to core memory for storage at its previous location.

The method of operation of a typical call in the system, assuming the incoming call is via an MF trunk can be described as follows. When a trunk circuit 10 recognizes the seizure from the originating office, it will provide an off-hook to the originating office and initiate a call-for-service to the marker 11. The marker 11 will check the equipment group and position scanners to identify the trunk that is requesting service. Identification will result in an assignment of a unique 4 digit 2/5 coded equipment identity number. Through a trunk-type determination, the marker 11 determines the type of receiver 16 required and a receiver/sender scanner hunts for an idle receiver 16. Having uniquely identified the trunk and receiver, the marker 11 makes the connection through the three-stage matrix switching network 12 and requests the marker buffer 17 for service.

The call-for-service by the marker 11 is recognized by the marker buffer 17 and the equipment and receiver identities are loaded into a receiver register of the marker buffer 17. The marker buffer 17 now scans the memory for an idle call store to be allocated for processing the call, under control of the call process controller 21. Detection of an idle call store will cause the equipment and receiver identities to be dumped into the call store. At this time, the call process controller 21 will instruct the receiver 16 to remove delay dial and the system is now ready to receive digits.

Upon receipt of a digit, the receiver 16 decodes that digit into 2/5 code and times the duration of digit presentation by the calling end. Once it is ascertained that the digit is valid, it is presented to the call processor 18 for a duration of no less than 50 milliseconds of digit and 50 milliseconds of interdigital pause for storage in the called store. After receipt of "ST," the call processor controller 21 will command the receiver 16 to instruct the trunk circuit 10 to return an off-hook to the

calling office, and it will request the code processor 22.

The code processor 22 utilizes the called number to check for EAS blocking and other functions. Upon completion of the analysis, the code processor 22 will send to the call processor controller 21 information to route the call to an announcement or tone trunk, at up to 4 prefix digits if required, or provide delete information pertinent to the called number. If the call processor controller 21 determined that the call is an ANI call, it will receive, accumulate and store the calling number in the same manner as was done with the called number. After the call process controller 21 receives "ST," it will request the billing unit 14 for storage of an initial entry in the billing unit memory. It will also command the receiver 16 to drop the trunk to receiver connection. The call processor controller 21 now initiates a request to the marker 11 via the marker buffer 17 for a trunk to sender connection. Once the marker 11 has made the connection and has transferred the identities to the marker buffer 17, the marker buffer will dump this information into the appropriate call store. The call processor controller 21 now interrogates the sender 19 for information that delay dial has been removed by the routing switch (crosspoint tandem or similar). Upon receipt of this information the call processor controller 21 will initiate the sending of digits including "KP" and "ST." The call process controller 21 will control the duration of tones and interdigital pause. After sending of "ST," the call processor 18 will await the receipt of the matrix release signal from the sender 19. Receipt of this signal will indicate that the call has been dropped. At this time, the sender and call store are returned to idle, ready to process a new call.

The initial entry information when dumped from the call store is organized into the proper format and stored in the billing unit memory. Eventually, the call answer and disconnect entries will also be stored in the billing unit memory. The initial entry will consist of approximately 40 characters and trunk scanner 25 entries for answer or disconnect contain approximately 20 characters. These entries will be temporarily stored in the billing unit memory until a sufficient number have been accumulated to comprise one data block of 1,370 characters. Once the billing unit memory is filled, the magnetic tape unit 26 is called and the contents of the billing unit memory is recorded onto the magnetic tape.

The final result of actions taken by the system on a valid call will be a permanent record of billing information stored on magnetic tape in multi-entry format consisting of initial, answer, and disconnect or forced disconnect entries.

Answer timing, force disconnect timing and other timing functions such as, for example, a "grace period" timing interval on answer, in the present system, are provided by the trunk timers. These trunk timers are memory timers, and an individual timer is provided for each trunk in a trunk scanner memory which comprises a status section and a test section.

The status section contains 1 word per ticketed trunk. Each word contains status, instruction, timing and sequence information. The status section also provides one word per trunk group which contains the equipment group number, and an equipment position tens words that identifies the frame. A fully equipped status section requires 2,761 words of memory representing 2,000 trunks spread over 60 groups plus a sta-

tus section "start" word. As each status word is read from memory, it is stored in a trunk scanner read buffer (not shown). The instruction is read by a scanner control to identify the contents of the word. The scanner control logic acts upon the timing, sequence and status information, and returns the updated word to the trunk scanner memory and it is written into it for use during the next scanner cycle.

The test section contains a maximum of 83 words: a 10 start word, a last programmed word, 18 delay words, two driver test words, one end-test word and one word for each equipment group. The "start test" word causes a scan point test to begin. The delay words allow time for scan point filters to charge before the trunk groups 15 are scanned, with the delay words containing only instructional data. The equipment group words contain a two digit equipment group identity and five trunk frame equipped bits. The trunk frame equipped bits (one per frame) indicates whether or not a frame exists 20 in the position identified by its assigned bit. The delay words following the equipment group allow the scan point filters to recharge before the status section of memory is accessed again for normal scanning. The Last Program word inhibits read and write in the trunk 25 scanner memory until a trunk scanner address generator has advanced through enough addresses to equal the scanner cycle time. When the cycle time expires, the trunk scanner address generator returns to the start of the status section of memory and normal scanning 30 recommences.

The trunk scanner memory and the trunk scanner read buffer are not part of the trunk scanner 25, however, the operation thereof is controlled by a scanner control which forms a part of the trunk scanner 25 of 35 the billing unit 14. The trunk scanner 25 maintains an updated record of the status of each ticketed trunk, determines from this status when a billing entry is required, and specifies the type of entry to be recorded. The entry includes the time it was initiated and the 40 identification of its associated trunk.

Scanning is performed sequentially, by organizing the memory in such a manner that when each word is addressed, the trunk assigned to that address is scanned. This causes scanning to progress in step with the trunk 45 scanner address generator. During the address advance interval, the next scanner word is addressed and, during the read interval, the word is read from memory and stored in the trunk scanner read buffer. At this point, the trunk scanner 25 determines the opeations to be 50 performed by analyzing the word instruction.

As indicated above, scanning is performed sequentially. If all trunks in all groups are scanned in numerical sequence beginning with trunk 0000, scanning would proceed in the following manner:

Step 1. Trunk 0000 located in frame 00 (lineup 0, column 0) in the top file, leftmost card position would be scanned first.

Step 2. All trunks located in frame 00 and the leftmost card position would be scanned next from the top file to the bottom.

Step 3. Scanning advances to frame 01 (lineup 0, column 1) and proceeds as in Step 2.

Step 4. Scanning proceeds as in Step 3 until frame 04 has been scanned.

Step 5. The scanner returns to frame 00 and Step 2 is repeated for the next to leftmost card position.

Step 6. The sequence just described continues until all 10 card positions in all 5 columns have been examined.

Step 7. The entire process is repeated in lineups 1 through 5. When a memory word instruction identifies a trunk group word, the status receivers are cleared to prepare for scanning the trunks specified in the group word. The trunk group digits stored in the trunk scanner read buffer (TSRB) are transferred into the equipment group register.

After the trunk group number is decoded, it is transformed into binary code decimals (BCD), processed through a 1-out-of-N check circuit, and applied to the AC bus drivers (ACBD). The drivers activate the scan point circuits via the group leads and the trunk status is returned to the receivers.

A group address applied to the drivers causes the status of all trunks in one lineup and one card position and all columns to be returned to the receivers. The group tens digit specifies the trunk frame lineup and the group units digit identifies the card slot.

When a status word is read from memory, it sets the previous count of a trunk timer (TT) into the trunk timer.

If the trunk is equipped and the forced disconnect sequence equals two (FDS = 2), a request to force release the trunk is transmitted to the marker 11. If FDS does not equal 2, the present condition of the ticketing contacts in the trunk is tested. If the instruction indicates that the trunk is in an updated condition (the trunks associated memory word was reprogrammed) it is tested for idle. If the trunk is idle, its instruction is changed to denote that it is ready for new calls. If the trunk is not idle, no action is taken and the trunk scanner 25 proceeds to the next trunk.

If the trunk is not in the updated condition and FDS=3, the trunk is tested for idle. If the trunk is idle, FDS is set to 0 and TT is reset.

If FDS does not equal 3 and a match exists between the present contact status and the previous contact status stored in memory (bits 5 and 6) the FDS memory bits are inspected for a count equal to one. If FDS = 1, TT is reset and the memory contact status is updated. If FDS does not equal one, TT is not reset.

During any analysis of a trunk status, a change in the contact configuration of a trunk is not considered valid until it has been examined twice.

One bit (SFT) is provided in each memory status word to indicate whether or not a change in status of the trunk was detected during the previous scan cycle.

When a change in status is detected, SFT is set to one. If SFT = 1 on the next cycle, the status is analyzed and SFT is set to zero.

If a mismatch exists between the present contact condition and that previously stored in memory, the status has changed and a detailed examination of the status is started.

If CT = 1, the trunk is busy and so the previous condition of the contact is inspected. If the trunk previously was idle, CM = 0. Before continuing the analysis, it must be determined if this is the first indication of change in the trunk status by examining the "second look" bit (SFT). If SFT = 0, it is set to equal one, and the analysis of this trunk status is discontinued until the next scanner cycle. If SFT = 1, the memory status is updated and SFT is set to equal zero.

If CT = 1, the trunk is cut through and CM is inspected to determine if the memory status was updated. If CM = 1, the GT contact status must differ from GM since it was already determined that a mismatch exists.

5 If GT = 0, answer has not occurred. If GT = 1, and this condition existed during the previous scan cycle, SFT = 1 also. If these conditions are true and FDS does not equal one, TT is advanced and answer timing begins. If these conditions persist for eight scanner cycles (approximately 1 second), answer is confirmed and an entry will be stored in the trunk scanner formatter (TSF). If answer is aborted (possibly hookswitch fumble) before the 1 second answer time (time is adjustable) expires, TT remains at its last count. When the 15 answer condition returns, answer timing continues from the last TT count. Thus, answer timing is cumulative.

After an answer entry is stored, which includes the TT count, TT is reset, SFT is set to zero, and the new contact status is written into memory.

If a mismatch exists and CT = 0, the previous state of this contact is inspected by examining bit 5 in the trunk scanner read buffer (TSRB). If CM = 1, the state of the terminating end of the trunk is tested. If GT = 1, then the condition of the trunk has just changed from answer to disconnect. If this condition existed during the previous scan cycle, SFT = 1 and a disconnect entry is stored in the TSF.

30 After the disconnect entry is stored, which includes the TT count, TT is reset, FDS and SFT are set to zero, and the new status is written into memory.

If a mismatch exists and the originating end of a trunk is not released, both CT and CM equals one. If GT = 0 after the previous scan cycle, FDS is tested. If this change just occurred, FDS does not equal one. Since FDS does not equal one, it will be set equal to one and TT will reset. FDS = 1 indicates that forced disconnect timing is in progress.

35 40 While the conditions just described exist, i.e., mismatch, CT = 1, CM = 1, GT = 0 and FDS = 1, TT will advance one count during each scanner cycle, if one half second has elapsed since the last scan cycle. TT will continue to advance until it reaches a count of 20 45 (approximately 10 seconds) when a forced disconnect entry will be stored in the TSF.

When the entry is stored, FDS is set at two indicating that the trunk is to be force released. After the entry is stored, which includes the TT count, TT is reset, SFT is set to zero, and the new status is written into memory.

50 55 After the status and test sections of the memory have been accessed, the Last Program word is read from memory and stored in the trunk scanner read buffer. This word causes read/write in the trunk scanner portion of memory to be inhibited and deactivates the scan point test. The trunk scanner address generator will continue to advance, however, until sufficient words have been addressed to account for one scan cycle. 60 65 When a predetermined address, the Last Address, is reached, block read/write is removed and the address generator returns to the Start Address (First Program Word) of the scanner memory.

As indicated above, the operation of the call process controller 21 revolves around the call store which is a section of memory allocated for the processing of a call. There are 77 call stores in the memory, and the

call process controller operates on these call stores sequentially.

Each of the call stores is assigned a unique time slot of 512 microseconds, and each time slot is further divided into eight subtime slots of 64 microseconds each. Each subtime slot is assigned to one row of the call store's memory. The subtime slots are generated by a memory logic subsystem, and are designated as RWP1, RWP2 . . . RWP8.

In FIG. 2, one of these call stores is illustrated, and it can be seen that each row consists of two physical memory words of 26 bits per word. The first 25 bits of each word are used for data and the last bit for parity.

The first and second rows are considered as control rows, where sequence states, timing of events during all progress, result of data analysis, and command generation are recorded. A portion of the first and second rows is also used to store the receiver and sender address. The third row stores the equipment identity, part of the type of call digits, and the prefix digits. The fourth row stores the calling number from ANI spill or from ONI operator, the originating area code index, the information digit, and part of the type of call digits. The fifth row stores the called number and the sixth row stores the class mark. The first and second rows are accessed again during subtime slots seven and eight, respectively.

In FIG. 3, a portion of the memory logic subsystem access assignment chart is illustrated, and reference may be made to it in conjunction with the description below, for the purpose of explaining the operation of the address generator dedicated to the call processor 18.

For every call store, the call processor 18 accesses the memory to read/restore and clear/write 12 consecutive words (six pairs), and then read/restore and clear/write the first four words (two pairs) again. Such a process calls for the address generator to advance forward 12 consecutive counts (six pairs), jump back 12 counts (six pairs), advance forward four consecutive counts (two pairs), jump forward eight counts (four pairs), and then repeat the same process for every call store, as illustrated in FIG. 5.

The address generator is illustrated in FIG. 4, and is a 14 bit address generator composed of two 14 bit counters 50 and 52. The counter 50 functions as two separate counters, a 13 bit counter 50b and a one bit counter 50a. The counter 50a is composed of one flip-flop which provides the least significant bit of the address (A₀ in FIG. 5) and keeps track of the even (word A) and odd (word B) addresses used in forming the word pairs.

The counter 50b provides the remaining 13 bits of the address (A₁-A₁₃ in FIGS. 4 and 5), and is advanced once per pair after both words A and B have been read and written back into the call store. The counter 50a is set after word A has been read (in order to read word B) and reset after word B has been written into the call store (in order to write word A), as per the access assignment chart in FIG. 3.

In order to return to the first two pairs, the counter 52 is provided. This counter 52 retains the last 13 bits of the address of the first pair, and this address is transferred to the counter 50b, to allow it to access the first two pairs again, while the counter 52 advances to the address of the first pair in the following call store. After

the counters 50a and 50b have advanced through the first two pairs for the second time, the address in the counter 52 (which is now the first address of the next call store) is transferred once more into the counter 50b, to provide the start address of a new cycle.

The pairs are identified by a system counter having a cyclic range of 1-8, and provides the RWP1-RWP8 pulses. The count cycle is as follows:

COUNT	WORD PAIR
1	1
2	2
3	3
4	4
5	5
6	6
7	1
8	2
1	1
2	2
.	.

More particularly, as can be seen in FIGS. 4 and 5, at the start, the counters 50b and 52 are preset to a start address (word A of the first call store), the counter 50a is reset to "0" and the pair count = 1. With the counter 50a reset to "0," the word A is read from the call store, during TX₀B. The TX₁B and clock A pulses set counter 50a to "1," and the word B is read from the call store, during TX₂B. During TX₁₂B, the word B is returned, either modified or unmodified, to the call store, and during TX₁₃B and clock A, the counter 50a is reset to "0," thus permitting the word A to be returned to the call store. The counter 50b is advanced by one count, when the OR gate 54 is enabled by the pair count = 1 and the AND gate 56 is enabled by the output of the OR gate 54 in coincidence with the clock A and the TX₁₅B pulses.

At this time, counter 50a is reset to "0" and the last 13 bits of word A of the next call store are set in counter 50b. During TX₀B, this word A of this call store is read from the call store. The sequence advances, as described above, until the words A and B of the first six pairs have been read and returned to the call store. In other words, the counters 50a and 50b have advanced forward 12 consecutive counts.

At this time, the pair count = 6 and the clock A pulses enable the OR gate 58 and the AND gate 60. The output of the AND gate 60 presets the counter 50b and causes the address stored in the counter 52 to be transferred into the counter 60b. This address corresponds to the address of the word A of the first call store (the start address) since the counter 52 has not been advanced as counter 50b advanced. The above described sequence of operation again is repeated, so that the first two pairs of words are again read and returned to the call store.

The pair count advances to pair count = 7 shortly after the address is transferred from counter 52 into counter 50b, and during TX₄A the OR gate 62 is enabled. Its output in coincidence with the pair count = 7 and the clock B pulse advances by one the count of counter 52. The count likewise is advanced by one in this manner, during the occurrence of each of the TX₅A, TX₆A, TX₇A, TX₈A and TX₉A, so that the address in the counter 52 now corresponds to the last 13 bits of the address of the next call store (call store N + 1 in FIG. 5).

The pair count = 8 pulse enables the OR gate 58, and its output in coincidence with the clock A and the TX15B pulses enable the AND gate 60, to again preset and transfer the address in counter 52 which, as indicated above, corresponds to the address of the next call store, into the counter 50b. Word A of this call store now is read, and the sequence of operation described continues for this call store, as well as the remaining call stores.

When the last address is reached, the counter 52 is preset, via the OR gate, to the start address which corresponds to the word A of the first call store.

It will thus be seen that the objects set forth above among those made apparent from the preceding description, are efficiently attained and certain changes may be made in carrying out the above method and in the construction set forth. Accordingly, it is intended that all matter contained in the above description or shown in the accompanying drawings shall be interpreted as illustrative and not in a limiting sense.

Now that the invention has been described, what is claimed as new and desired to be secured by Letters Patent is:

1. In a common control communication system including a core memroy, a plurality of call stores in said core memory, each of said call stores including a plurality of word pairs, and a system clock for providing a plurality of clock pulses and a plurality of timing interval pulses, an address generator for addressing said core memory to read out each of said plurality of word pairs in a call store in a consecutive fashion until a predetermined number of word pairs have been read out and then to re-address and read out the first two word pairs in a call store a second time before advancing to address the first word of the first word pair of the succeeding call store until all of said call stores have been accessed, said address generator comprising: a first and a second counter means for providing a plurality of address bits for addressing said plurality of word pairs, said first and second counter means initially being preset to a start address corresponding to the first word of the first word pair of the first call store; first gating

means operated by established ones of said clock and timing interval pulses to advance by one the count of said second counter means until the count thereof has advanced forward a predetermined number of consecutive counts to thereby address consecutive words of said word pairs, second gating means operated when said second counter means has advanced forward said predetermined number of counts to transfer said start address from said first counter means into said second counter means, thereby setting said second counter means to again address the first word of the first word pair of the first call store; third gating means; said first and third gating means being operated by established ones of said clock and timing interval pulses to simultaneously advance by one the count of both said first and second counter means, whereby said second counter means again addresses the words of the first two word pairs and said first counter means advances to the address corresponding to the first word of the first word pair of the succeeding call store; said second gating means again being operated to transfer the address in said first counter means into said second counter means to thereby set said first counter means to address said first word of the first word pair of said succeeding call store; said address generator continually sequencing as above until all of said call stores have been accessed.

2. The address generator of claim 1, wherein said first counter means comprises a binary counter.

3. The address generator of claim 1, wherein said second counter means comprises a binary counter and a flip-flop circuit, said flip-flop circuit providing the first address bit in a word address and said binary counter providing the additional address bits of said word address.

4. The address generator of claim 3, wherein said second counter means comprises a binary counter.

5. The address counter of claim 4, further including fourth gating means operated by predetermined clock and timing interval pulses to advance the count of said first counter means.
